Primary Examiner — Darlington Ly(74) *Attorney, Agent, or Firm* — Michael Best & Friedrich LLP(57) **CLAIM**

We claim the ornamental design for a power tool, as shown and described.

DESCRIPTION

FIG. 1 is a front perspective view of a power tool showing our new design in accordance to a first embodiment; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; FIG. 7 is a bottom plan view thereof; and, FIG. 8 is an enlarged cross-sectional view thereof, in which the section cut plane is indicated by line 8-8 in FIG. 2. The present application is directed to the design illustrated in the figures. The broken lines shown in the figures illustrate portions of the power tool and form no part of the claimed design.
